Inv. to
Casimir Amster.

United States Patent Office.

CASIMIR AMSLER, OF ST. LOUIS, MISSOURI.

Letters Patent No. 95,302, dated September 28, 1869.

IMPROVEMENT IN SAWING-MACHINES.

The Schedule referred to in these Letters Patent and making part of the same.

To all whom it may concern:

Be it known that I, CASIMIR AMSLER, of St. Louis, in the county of St. Louis, and State of Missouri, have made certain new and useful Improvements in Scroll-Sawing Machines; and I do hereby declare the following to be a full and true description thereof, reference being had to the accompanying drawings, and to the letters of reference marked thereon.

This invention relates to the arrangement of the pitman moving the saw with a bead-slide, in such wise that the operator, by moving the bead-slide, may vary the stroke of the saw as he may see proper, and this without any interruption of the movement of the saw. The said saw may, therefore, be applied to the varying kinds of scroll-sawing in which curves of different radii are made, with economy of time and labor.

This invention further relates to certain details of construction hereinafter more fully shown.

To enable those herein skilled to make and use my said improvement, I will now fully describe the same, referring to the accompanying

Figure 1 as a front view;

Figure 2, as a longitudinal view; and to

Figure 3, as a detail elevation, showing the sliding head of the saw-pitman and its adjustment.

I support the scroll-saw, and its operating-devices, upon a suitable frame, usually, of wood or cast-iron, A.

Upon the plate A', of said frame, is the bracket B, which has, at its front end, the usual guides b, for the saw-lifter C, this being connected by a strap, e, to a bent lever, D, which has its fulcrum on the vibrating bar E, at e.

The vibrating bar E is pivoted at e' on a standard upon the bracket B.

To the lower end of the lifter C the saw F is attached, it being connected at its own lower end to a slide, G, moving between proper guides.

To detach the saw, the operator releases the clamp holding the lever D down on the bar E, so that the lever D may rise to a nearly vertical position. The band e then is relaxed, and the lifter C may be moved down to release the saw-blade. By drawing the lever D tightly against the bar E, the tension of the saw-blade may be increased.

The slide G has a link, g, connecting with a rock-bar, H, which has its fulcrum on the frame A at b, and the end hereof is connected, by a link, h, with the vibrating bar E, thus completing the attachment.

The slide G is moved by a pitman, I, which has a sliding head, i, moving on a rock-lever, K, the fulcrum whereof is at k on the frame A.

The end of the lever K connects, by a rod, L, with the crank-wheel or disk M, this being on a shaft, m, resting upon bearings in the main frame.

Power is transmitted to the shaft m by a pulley and band from the driving-wheel N, the shaft whereof is moved by a treadle-attachment (or other power-device) in the usual manner.

In order to vary the stroke of the pitman I, (as in the nature of this invention,) the sliding head i is moved longitudinally on the lever K, to increase or diminish its distance from the fulcrum k. This is done by attaching the rod O to the said head i, said rod connecting with an arm, p, on the shaft P. On the same shaft is the arm q, which is moved by the hand-bar Q. The latter has notches for fixing its position when adjusted, whereby the operator is enabled to readily move the sliding head i, and thus vary the stroke of the saw whilst cutting or sawing therewith, or, when the hand-bar Q is held by one of its notches to its position relative to the main frame, the stroke of the saw remains invariable, as is usually the case.

This feature of adjustment of stroke is of advantage when using gig-saws, to pass the stuff about the same. For this purpose the saw is moved entirely below the table A' by using the hand-bar Q to move the slide i to the end of the lever K, then the stuff is moved over the saw, which rises up through the hole in the stuff, and may thereupon be adjusted to cut without further detention.

To clear the stuff of the sawdust, so that the scroll-marks may be clearly visible to the operator, I arrange the clamp-foot R hollow. Within the same, I arrange a piston-head, moved by a piston-rod, r, connecting with the bar E. By the vibration of this bar, a current of air is forced upon the table, to clear off the sawdust. To draw in the air, the foot R has a series of perforations.

Having thus fully described my invention,

What I claim, is—

The pitman I, arranged with a sliding head, i, and combined with a rock bar K, substantially as set forth.

CASIMIR AMSLER.
